UNITED STATES PATENT OFFICE.

LONZO JOHNSON, OF INDIANAPOLIS, INDIANA.

DESIGN FOR A LAMP.

Application filed March 17, 1924. Serial No. 8,957. Term of patent 3½ years.

To all whom it may concern:

Be it known that I, LONZO JOHNSON, a citizen of the United States of America, residing at the city of Indianapolis, in the county of Marion and State of Indiana, have invented a new, original, and ornamental Design for Lamp, of which the following is a specification, reference being had to the accompanying drawing, forming part thereof. The figure is an elevational view of a lamp, showing my new design.

I claim:

The ornamental design for a lamp, as shown.

LONZO JOHNSON.
